UNITED STATES PATENT OFFICE.

MILTON BRADLEY, OF SPRINGFIELD, MASSACHUSETTS, ASSIGNOR TO THE UNION MANUFACTURING COMPANY, OF NEW BRITAIN, CONN.

DESIGN FOR BUTT-HINGES.

Specification forming part of Design No. **6,949**, dated October 7, 1873; application filed September 24, 1873.
[Term of Patent 7 years.]

To all whom it may concern:

Be it known that I, MILTON BRADLEY, of Springfield, in the county of Hampden and State of Massachusetts, have invented a new Design for Butt-Hinge; and I do hereby declare the following, when taken in connection with the accompanying drawings and the letters of reference marked thereon, to be a full, clear, and exact description of the same, and which said drawings constitute part of this specification, and represent, in—

Figure 1, a rear view of one leaf of a hinge; and in Fig. 2, a face view of the same.

This invention relates to a design for the ornamentation of butt-hinges; and it consists in the ornamentation of the several parts as shown in the accompanying illustrations, and as hereinafter described.

The front or face of the leaves of the butt are ornamented with a border around the edge, the surface of the panel within the border filled with tracery, as seen on the leaf, Fig. 2, the solid black indicating the raised portions, the tracery and border being flush, the remaining or depressed portions being matted or otherwise finished. This ornamentation is shown

as made upon a facing, and that secured to the leaf of the hinge, but may be formed directly upon the leaf of the hinge. Upon the rear of the hinge a depression is formed upon the exposed portion, and within this a raised ornamental work flush with the surface of the hinge, as denoted in solid black on the leaf, Fig. 1. This is formed in the process of casting the hinge. The tips of the pintle are formed with a raised ornament, as denoted in solid black, the remaining surface matted or otherwise finished.

I claim as my invention—

1. The design for the face of a butt-hinge, as herein described and shown in the accompanying illustrations.

2. The design for the rear of a butt-hinge, as herein described and shown in the accompanying illustrations.

3. The design for pintle-tips, as herein described and shown in the accompanying illustrations.

MILTON BRADLEY.
